UNITED STATES PATENT OFFICE.

WILLIAM W. RAMSEY, OF DAYTON, OHIO, ASSIGNOR OF ONE-HALF TO
AUGUST TEGELE, OF SAME PLACE.

LUBRICATING OIL-CUP.

SPECIFICATION forming part of Letters Patent No. 257,611, dated May 9, 1882.

Application filed November 1, 1880. (No model.)

To all whom it may concern:

Be it known that I, WILLIAM W. RAMSEY, of Dayton, in the county of Montgomery and State of Ohio, have invented new and useful 5 Improvements in Lubricating Oil-Cups, of which the following is a specification.

My invention relates to improvements in lubricating oil-cups, as hereinafter described and specifically claimed.

10 My invention pertains to that class of lubricators which are attached to the supply-pipe of a steam-engine, and by which the oil is automatically fed into the steam, and is thereby conveyed to the valves and piston of the engine.

15 The accompanying drawings are made a part of my specification, in which like letters of reference designate like parts.

Figure 1 is a front elevation of the lubricating oil-cup. Fig. 2 is a cross-section on the 20 line *x x*, Fig. 1. Fig. 3 is a central longitudinal section of the same.

A represents a cylindrical vessel serving as a reservoir for the oil. B is a glass tube, supported at the top and bottom by pipes attached 25 to the side of the reservoir, and through which the oil is supplied to the same, and within which the amount of oil is discovered in the same. The nut H closes the orifice at the top and the plug I closes the orifice at the bottom 30 of the glass tube, and through the latter the oil is withdrawn from the reservoir. To the top of the reservoir is attached the stop-cock T, used to give vent while filling or drawing off the contents. To the lower end of the reservoir is screwed the part O, the left end of 35 which supports the stop-cock K and the right end the glass tube C and plug P. At the center of the part O is attached the oil-tube S, which extends to near the top of the reservoir, 40 and is centrally situated relative to said reservoir. The orifice of this tube is continuous to the plug, and that portion within the part O is closed by the stop-cock K, which serves the double purpose of arresting the flow of oil 45 if the visible feed-tube becomes broken and regulates the flow of the oil to the steam-pipe. The plug P closes the opening through which the visible feed-tube C is placed in position. This plug has a circumferential groove on a 50 line with the orifice of part O, and a small orifice within this groove communicates with a central orifice, which extends to the top of the plug.

To the part G are screwed the steam-condensing chamber D and the oil-reservoir A. 55 This part G is cast solid with the exception of the pipe-extension G' to the right. The left end supports the stop-cock J, which closes the orifice U, the office being to close this orifice only when either of the glass tubes breaks. The 60 pipe-extension G' terminates in a thread, by which attachment is made to the induction steam-pipe of an engine. Of this extension a part extends downward to embrace the upper end of the visible feed-tube. At a right angle 65 to this part is a rear extension, which supports the stop-cock M. This stop cock closes the orifice leading to the visible feed-tube C, and is used to prevent the escape of steam while filling and in case of breakage. 70

The steam-pipes E and F screw into the part G, and the orifice in said part is continuous from the end of one to the other. The outer end of the pipe F turns up to prevent the oil being carried into the condensing-chamber D. 75

The operation is thus described: The stop-cocks J and M being closed, the reservoir A is filled with oil. These cocks are now opened. The steam entering the condensing-chamber D, water forms therein, and flowing into the 80 reservoir causes the oil to flow into the oil-tube C, thence to collect in drops on the point of the plug P, and thence ascend in drops through the visible feed-tube C, to enter the pipe-extension G' and be carried to the valve and piston 85 of a steam-engine to effect their lubrication.

Having fully described my invention, what I desire to secure by Letters Patent is—

The herein-described steam-actuated lubricator, consisting of the metal oil-receptacle A and steam-condensing chamber D, from which steam-pipe connection E F extends, the glass indicator-tubes B and C, arranged at the side of the oil-receptacle, with which they are connected, the pipes R, S, O, and G', having connecting-ducts, as specified, and the valves J K M, located as shown, the whole being constructed and arranged to operate substantially in the manner set forth. 95

WILLIAM W. RAMSEY.
